UNITED STATES PATENT OFFICE

137,402

DESIGN FOR A FABRIC PATCH MENDING MACHINE

Edward N. Simmons, Chicago, Ill.

Application December 10, 1943, Serial No. 111,982

Term of patent 7 years

To all whom it may concern:

Be it known that I, Edward N. Simmons, a citizen of the United States, residing at Chicago, in the county of Cook and State of Illinois, have invented a new, original, and ornamental Design for a Fabric Patch Mending Machine, of which the following is a specification, reference being made to the accompanying drawing, forming a part thereof.

In the drawing:

Fig. 1 is a front elevational view of a fabric patch mending machine embodying my new design;

Fig. 2 is a plan view thereof; and

Fig. 3 is an end elevational view thereof.

I claim:

The ornamental design for a fabric patch mending machine, substantially as shown.

EDWARD N. SIMMONS.
